WATER FRONT RETAINING WALL AND METHOD OF CONSTRUCTION

David Homer Hayden, Sarasota, Fla., assignor to Beach & Shore, Inc., New York, N.Y., a corporation of New York

Application February 12, 1953, Serial No. 336,539

9 Claims. (Cl. 61—49)

The present invention concerns a water front retaining wall and method of constructing the same, and refers more particularly to improvements in the wall of my Patent No. 2,525,547, comprising a wall, a novel pile for the wall, a novel relation of the other elements of the wall to the pile, a novel selection and sequence of successive operations by which the wall is constructed.

It is usually necessary to employ a coffer dam when building foundations of piers or walls below water level, and such a dam is also sometimes necessary in constructing concrete piles for a wall.

An object of the present invention is the provision of a concrete wall and method of constructing the same which can be built without the use of coffer dams, caissons, footings, or other such equipment.

A further object is that the work may proceed for a reasonably long period of time, despite the rise and fall of tide.

Another object is that the wall shall be substantially as rigid and sturdy as if built with the aid of a coffer dam.

An important object is economy of material and labor in the construction of the wall.

In accomplishing the objects of the present invention, I prefer to use precast reinforced concrete planks and reinforced concrete piles, the lower portions of the piles being precast. The lower portions further have slots extending vertically on opposite sides, and may be jetted into position, and the planks then slid into the slots, also being jetted if necessary. The top of the lower portion is substantially at one quarter tide level, and the top plank engaged in this lower portion projects upwardly by about half the width of the plank.

The remaining planks are then set in position and the upper portions of the piles, as well as landward extending heels, buttresses and top coping if desired, are poured around the planks and become integral with them and with the lower portions of the piles.

The work is scheduled so that the pouring commences when the tide is three quarters out, and since the top of the lower pile portion is at one quarter tide level and further since the poured concrete is substantially all above or at this level, the lowest part of the poured concrete has about three hours to dry before the returning tide will reach it.

Other objects of this invention will in part be obvious and in part hereinafter be pointed out. The invention accordingly consists in the features of construction, combinations of elements and arrangements of parts which will be exemplified in the constructions and methods hereinafter described. In the accompanying drawing, in which is shown one of the various possible illustrative embodiments of this invention:

Figure 1 is a side elevation of a precast lower portion of a reinforced concrete pile according to the invention.

Figure 2 is a section on the line 2—2 of Figure 1.

Figure 3 is a vertical section through the wall at a point intermediate the piles.

Figure 4 is a section on the line 4—4 of Figure 3.

2

Figure 5 is a section on the line 5—5 of Figure 3.

Figure 6 is a fragmentary front elevation of the wall. Fig. 7 is a view corresponding to that of Fig. 6 but showing the wall supported by spaced pile portions between which are the planks illustrated as being broken away.

Fig. 8 is also a section on line 4—4 of Fig. 3 and showing how each of the spaced piles in Fig. 4 is provided with a slab like heel portion 25.

10 Referring now in detail to the drawings, the wall 10 comprises a plurality of spaced piles 11, the latter comprising lower portions 12, each such portion comprising the precast concrete body 13 whose height is substantially half the height of the wall. Body 13 comprises 15 the elongated substantially vertically extending main portion 14 and the rib portion 15 integral therewith and extending rearwardly therefrom. Steel reinforcing rods 16, 17 are cast into the body 13 and constitute the remainder of lower portion 12 of pile 11.

20 Main portion 14 is formed with the vertically extending grooves or slots 18 on opposite sides thereof.

In building a wall according to the present invention, the lower portions 12 are jetted to a depth at which their top surfaces 19 are substantially at one quarter tide level, that is, one quarter of the distance up from mean low tide level 20 to mean high tide level 21.

25 By jetting is meant the conventional practice of sinking an object into the earth by directing a powerful stream of water against the earth below or immediately adjacent

30 the object. The earth is washed away by the stream and the object settles by gravity. In jetting a pile, a hose or pipe is used with a nozzle at the lower end. The nozzle is close to the pile and may be pointed so as to wash away earth under the pile. Sometimes it is necessary to operate the jet all around the pile in order to wash away the underlying earth and permit the pile to sink to the desired depth.

35 Precast concrete planks 22, 23 are then engaged in the grooves or slots 18 of the adjacent portions 12, with the assistance of jetting if necessary. Other planks 24 are further engaged in the slots 18, projecting for about half their height above the body portion 13. The above described work should either be scheduled for completion 40 at the time the tide is three quarters out so that work may continue from such point, or work may be interrupted and recommended at one quarter tide level of ebb tide.

45 Substantially as a single continuous operation beginning at quarter tide level of ebb tide, a slab like heel portion 25 of concrete is poured, surrounding the reinforcing bars 26, 27 and planks 24 and in intimate contact with body portion 13, becoming integral with all of the same.

50 Continuing the operation, precast concrete planks 28, 29, are set in position and upper portions 30 of piles 11 are poured around them, buttress 31 and coping 32 with reinforcing rods 33, 34 also being poured at substantially the same time to complete a unitary structure integral 55 with the lower portions 12 of piles 11. The poured portions above described will have three hours or more of exposure to air before the returning tide will reach the lowermost portions thereof.

55 As clearly seen from the drawings, the upper portion 60 of the wall and in particular planks 28, 29 slope landwardly and upwardly and the entire wall is a unitary continuous rigid construction.

65 It will thus be seen that there is provided a device and method in which the several objects of this invention are achieved, and which is well adapted to meet the conditions of practical use.

70 The reason for the openings between planks as shown

in Fig. 3 is to provide a seepage space and yet hold the soil against coming out.

Those skilled in the construction of retaining walls and the like will understand a reason for the large area flat heel portion 25 illustrated is to be to engage any soil or sand contiguous the lower surface of the heel and be able thereby to distribute stresses from pressure against outer face of the wall. The buttress 31 and rib 15 being in alignment on the landward side of the piles and wall of this invention and secured to the heel portions 25 reinforces the wall against flexure longitudinally of the piles from outside water pressure.

An advantage in the process of this invention resides in elimination of the need for longer, more cumbersome and difficult to handle, precast piles, or else the elimination of the necessity for costly coffer dams and pumping apparatus where under prior practice, cast-in-place piles have been desired. As shown in the drawing this is the first retaining wall supported entirely by reinforced precast and built up cementitious piles. No supports spaced from the wall are needed. One feature contributing to this new advantage in simplicity of construction is the water seepage passages between planks minimizing the likelihood of a substantial unbalanced force due to the water being higher on one side of the wall than on another. Another feature contributing to that new result is the width of the precast pile of Fig. 1 being several times the thickness of the wall planks inserted between the piles. The process of this invention is believed to be the first to lengthen reinforced cementitious precast piles after being set when such piles are of the type supporting cementitious or other planks between pairs of the set piles. By "lengthen" is meant a build up of a greater amount than is encountered in placing a usual coping on a wall. For example this invention lengthens the original set pile by as much as about 100% of the original length, as shown in the drawing.

What is claimed is:

1. The method of building a water front retaining wall comprised of generally vertically extending reinforced cementitious piles and substantially horizontally extending planks, said method including inserting lower precast portions of said piles into a floor for the water with the tops of said lower precast pile portions above low water level and below mean high tide level, sliding the ends of some of said planks into longitudinal grooves in the sides of said precast lower pile portions, placing additional planks above those engaging said lower precast pile portions, said additional planks being arranged to form a space between their longitudinally adjacent ends, in prolongation of said lower precast pile portions, lengthening said lower precast pile portions upwardly an amount equal to at least about a major portion of the length of said lower precast pile portions by pouring upper end portions onto said lower precast pile portions and around the longitudinally spaced ends of said additional planks, and beginning said pouring at about a quarter tide level during an ebb tide.

2. The method of building a water front retaining wall comprised of generally vertically extending reinforced cementitious piles and substantially horizontally extending planks, said method including inserting lower precast portions of said piles into a floor for the water with the tops of said lower precast pile portions above mean low water level and below mean high tide level, sliding the ends of some of said planks into longitudinal grooves in the sides of said lower precast pile portions, placing additional planks above those engaging said lower precast pile portions, said additional planks being arranged to form a space between their longitudinally adjacent ends, in prolongation of said lower precast pile portions, adding to the length of said lower precast pile portions an amount equal to about 100% of the

length of said lower precast pile portions by pouring upper end portions onto said lower precast pile portions, around the longitudinally spaced ends of said additional planks, said last mentioned pouring forming substantially simultaneously heel portions and buttress portions both on a landward side of said upper end portions, and beginning the pouring of said upper end portions at about quarter tide level of ebb tide.

3. A process of erecting a water front retaining wall 10 of precast cementitious planks generally normal to and between piles, said process comprising inserting into and beneath a floor for the water precast lower pile portions of less height than the finished wall but of a height when set extending above the level of mean low tide and below mean high tide level, sliding lower planks into grooves in the sides of said precast pile portions and between pairs of said precast pile portions extending to adjacent the tops of said precast pile portions, raising the height of said wall by casting an additional upper 20 pile portion onto the precast pile portions, and adding planks above and generally parallel to said lower planks with their ends secured to upper pile portions, the casting of an upper pile portion being begun after an ebb tide has exposed a top of a precast lower pile portion and being completed before a rising tide has returned to a level at which casting of said additional upper pile portion was begun.

4. A process according to claim 3 in which said precast pile portions are provided on their landward side with 30 a strengthening rib, and casting a buttress in substantial alignment with said rib and when the height of said wall is raised by said additional upper pile portion.

5. A process according to claim 4 in which a heel is cast between said rib and buttress and substantially simultaneously with the casting of said buttress.

6. A process according to claim 3 which comprises casting said additional upper pile portion onto said precast pile portions when an ebb tide is below the top of a set pile and has progressed about 75% of its course 40 whereby the newly cast length will have about three hours to set before a rising tide reaches its lower portions.

7. A water front concrete retaining wall comprising spaced concrete piles each having a landwardly extending rib, a generally horizontal slab-like heel portion on 45 said rib and on each of said piles above the level of mean low tide and adjacent a mid-portion of said pile, precast concrete planks projecting into a recess in each pile on opposite sides, there being an opening for seepage 50 between each pair of planks, each such opening extending longitudinally of said planks, extending below the level of mean low tide and above the level of mean high tide on said pile, a coping on said planks and piles, and a buttress constituting a backing for said planks and pile portions above said heel portion, said 55 buttress rising from said heel portion and being integral therewith and in substantial alignment with said rib on the landward side of said pile.

8. A process of erecting a water front concrete retaining wall comprising setting precast spaced reinforced concrete piles each having an integral rib, said piles each having a length of but a portion of the length of the piles when finished and with the tops of said precast piles extending above the level of mean low tide and below mean high tide level, sliding precast planks into grooves on the sides of said precast piles with said planks extending below the level of the mean low tide, with a seepage space extending longitudinally between each pair of planks, beginning the casting of a generally horizontal heel portion onto the top of each precast pile and on top of said integral rib on a landward side of the pile and in rear of said planks during an ebbing tide when the water level is at about one quarter of the tide height from the level of mean low tide, integrally casting a buttress and an upper portion of said

pile onto said precast portion and rib with said heel portion, placing additional precast planks upon those already in place to have the later added planks also provided with similar seepage openings, the piles being lengthened by being cast around the ends of the later added planks, and pouring a coping on top of said piles and planks, at least some of the upper poured portions being cast during an ebbing tide and in time to take a set before rising tide reaches it.

9. A water front retaining wall comprising cementitious planks between cementitious piles, each pile having a longitudinal rib on a landward side extending above mean low tide level, a slab like generally horizontal heel portion carried above and contiguous to said rib in a central portion of said pile, and a buttress rising from 15 said heel portion in general alignment with said rib and integral with said rib and heel portion and an upper portion of said pile, said buttress and heel portions also being on the landward side of each pile said planks being provided with water seepage spaces between them whereby said wall is reinforced by said rib, heel portion, and buttress, and said seepage spaces tend to minimize an unbalanced static head of water on one side of said wall, said planks extending below the level of mean low tide and above the level of mean high tide. 20 25
